JOHN H. VICKERS, OF HUDSON, NEW YORK, ASSIGNOR TO INTERNATIONAL BITUMENOIL CORPORATION, OF NEW YORK, N. Y., A CORPORATION OF DELAWARE

RETOURT

Application filed May 18, 1926. Serial No. 109,834.

The present invention relates to a retort for the recovery of petroleum oils and gas from oil shales and other carbonaceous materials by means of an efficient primary retort and of the subsequent distillation of the products derived from the carbonaceous material in the liquid phase, to various fractions, all of which is accomplished in an economical manner from the standpoint of the utilization of fuel. The retort proper comprises an inclined rotating tube or cylinder through which the shale or other carbonaceous material to be treated passes, and while passing through this cylinder it is progressively heated from a relatively low to higher temperatures by the application of heat in separate zones maintained by novel and practical means. In addition to this retort chamber, there are furnace chambers located adjacent the retort and adjacent the several heat zones of the retort cylinder, and these chambers are separately heated, partly or wholly, by the heat created from the source of heat which is utilized for heating the carbonaceous material in the cylinder. Associated with each of these several heat chambers are suitable stills in which the evolved petroleum or other materials derived from the carbonaceous material is fractionated or distilled off at different specific gravities, the several stills handling the product in the liquid phase. The main object of the invention is to provide for the recovery of a maximum quantity of high quality petroleum from oil shale, and the distillation of the recovered petroleum into different fractions, all in a continuous process and with the maximum conservation of fuel. In addition, the present device, while performing all of these functions in their consecutive order, and operating simultaneously, is simple and compact in construction. In the preferred construction of the invention the carbonaceous material progresses by gravity through the revolving retort cylinder and the liquid under treatment in the several stills progresses therethrough by gravity.

In addition to separating the petroleum into different fractions by distillation, I also provide a unit operating in conjunction with

these stills for cracking different oil fractions and residues of the product to increase the percentage of gasoline produced in the apparatus. Other advantages and results will be set forth in connection with the following detailed description of my invention.

In the drawings forming part of this application,

Figure 1 is a side elevation of the parts in section showing one embodiment of my invention,

Figure 2 is a plan view thereof,

Figure 3 is a sectional view taken near the left hand end of the cylinder.

Figure 4 is an end view of the apparatus looking at the left hand end of Figure 2, and

Figure 5 is a cross sectional view through the revolvable cylinder.

In the drawings I have shown a long cylindrical retort 1 which is preferably mounted in an inclined position in order that the shale or other carbonaceous material may progress lengthwise therethrough by gravity. In the drawings I have shown this cylinder provided at one end with an annular flange 2 which is bolted to the cylinder to form a bearing member which rests upon and revolves freely in relation to the roller trunnions 3. Adjacent the opposite end of the cylinder there is a similar annular ring 4 attached thereto, and this rests upon roller trunnions 5 arranged at opposite sides of the vertical center of the cylinder. Preferably the front rollers 3 have flanges between which the member 2 engages to prevent longitudinal shifting of the cylinder, whereas the rear rollers 5 may have flat tops in order to allow the member 4 to shift as the expansion and contraction of the cylinder require.

I have provided a gear 6 which is attached to the forward end of the cylinder, and power may be applied from any suitable source (not shown) to this gear for the purpose of revolving the retort cylinder upon the supporting rollers, in order that the shale or other material may be turned over while it is progressing through the retort chamber in order to subject all portions to the heating action. The shale or other material to be treated is fed into a hopper 7 from which

it passes through a tube 8 into an inclined chamber 9; and within the latter there is a screw conveyor 10 for forcing the material toward the left in Figure 1, through the chamber 9 and into the receiving end of the revolving cylinder. I prefer to arrange an air sealing valve 11 within the tube 8 to exclude air from reaching the retort chamber, and the use of such device is well known. At 10 the lower or discharge end of the cylinder 1 there is a vertical discharge tube 12 which is in communication with the interior of the cylinder, and this receives the spent shale and discharges it into a horizontal chamber 15 13 arranged at the bottom thereof, and in the latter chamber there is a screw conveyor 14 which is revolved by suitable power, for feeding the spent shale along the chamber 13 to the outlet or discharge opening 15. The 20 tube 12 is continued upwardly above the end of the cylinder to provide a medium for collecting the vapors which are evolved from the shale in the retort chamber, and this collecting chamber discharges the vapors into 25 a pipe 16. Within the collecting chamber 17 there is a revolving screen 18 through which the vapors are obliged to pass, and this serves to collect any dust or solid particles which tend to rise with the oil vapors. 30 I prefer to provide a brush 19 in contact with the rotating screen for the purpose of dislodging the particles collected by the screen, and these particles may fall down the tube 12 and be discharged with the spent shale. 35

The screen 18 is inclined the same as the retort cylinder so that if any particles work through it they will travel by gravity toward the left hand end of the screen in Figure 1 and discharge downwardly off the same into the tube 12. The frame of the screen is provided with a gear 85 and this gear is operated by means of a gear 86 arranged on the end of the retort cylinder within the tube 40 45 12, 17. As the cylinder revolves, the motion is transmitted through the gears 86, 85 to the screen and this causes the latter to revolve in contact with the brush 19.

I prefer to construct the revolving retort cylinder of inner and outer concentric tubes or cylinders 20, 21 spaced apart, and to fill the space between these cylinders with a body of heat equalizing material 22 which will serve to equalize the heat applied to the shale throughout one of the heat zones. Preferably there is a separate body of such equalizing material for each heating zone of the cylinder.

The inclined, revolvable cylinder is surrounded throughout the greater part of its length by means of a wall structure, preferably made of fire brick or other refractory material; and in the drawings I have shown the structure comprising a bottom wall 23, 60 65 side walls 24, 25 and a top wall 26 surround-

ing the revolvable cylinder. The forward end of this structure has an in-turned wall 27 having an opening 28 just sufficiently large to clear the periphery of the revolving cylinder. Spaced from this first wall is a similar wall 29 serving as a partition and this likewise has a central opening just sufficient to clear the periphery of the cylinder. These walls, together with the top, bottom and side walls, form a combustion chamber 30 of more or less 75 annular shape surrounding a section of the revolving retort cylinder, and this may be considered as the first heating zone of the retort. At a distance from the wall 29 there is a similar wall 31 which is also provided 80 with an opening sufficient to clear the periphery of the cylinder, and this wall, together with the inturned wall 29 forms a combustion chamber 32 surrounding the cylinder, and this may be considered as the second heating 85 zone of the retort. I have shown another inwardly extending or dividing wall 33 spaced from the wall 31 and these two dividing walls form a combustion chamber surrounding the cylinder similar to those previously described; 90 and this may be considered as the third heating zone of the retort. There is also shown another in-turned dividing wall 34 at the end of the structure, which is provided with a similar opening to clear the cylinder, and this, together with the wall 33 forms a combustion chamber 35 surrounding the cylinder, and this constitutes the fourth heating zone. It will be understood that although I have shown the enclosure divided into four 100 heat zoning compartments, the device may be made with either a lesser or greater number of such compartments, according to the capacity of the apparatus, and various other factors. It will be observed that the enclosing structure may be inclined to correspond with the inclination of the cylinder. There is provision made for supplying heat to the lower portion of each of these combustion chambers, and in the drawings I have shown as an example three burners 36 each controlled by a suitable valve 37 for projecting flames through the front wall 24 of the enclosure into the lower portion of the first combustion chamber 30, so that the flame is projected across this chamber below the revolving cylinder, and preferably below the carborundum plates 38 disposed across the combustion chamber. The flames projected from these burners are prevented from acting 105 directly upon the cylinder by the intervening carborundum plates, so that there will be no possibility of the flames coming into direct contact with the cylinder and causing spot heating and scaling of its outer surface. I 110 have shown a similar set of burners 39 for projecting flames across the second combustion chamber 32 and I have likewise provided carborundum plates over these burners for the same purpose as the corresponding plates 115 120 125 130

in the first compartment. I have also shown similar burners 40 for the third compartment, and similar burners 41 for the fourth compartment. The number and capacity of these burners for the different compartments will be so arranged that the several combustion chambers will be heated progressively to higher temperatures, starting from the first chamber at the right in Figure 1, which will be heated to a relatively lower temperature, whereas the second, third and fourth compartments will be progressively heated each to a higher degree than the first one, and to each compartment preceding it. This difference of temperature may be controlled by using burners of greater capacity in the different compartments, or as shown in the drawings, a greater number of burners may be used for the higher temperature compartments than those for the lower temperature compartments. The burners are supplied from any source of fuel supply which may be gas, oil or other fuel, by means of the feed pipe 42. Preferably, the burners are constructed to admit a sufficient portion of air to supply oxygen for combustion and the fuel may be supplied to the burners under pressure.

There is a foundation structure arranged laterally at one side of the structure which encloses the revolving cylinder, and I have shown this as composed of a bottom wall 43, front and rear walls 44, 45, and suitable end walls; and these walls are shaped to receive and support the cylindrical stills which constitute the several units of the oil refining apparatus. As shown in Figure 3 there is a pocket formed in the walls 44, 45 to receive a portion of a still and to support the same above the floor 43 so that there is formed a heating chamber 46 extending across and under the still. In the side wall 25 of the first structure there is an opening 47 permitting communication between one of the combustion chambers under the revolving cylinder, and with the heating compartment 46 under one of the stills. I prefer to arrange a still in line with each of the combustion chambers as shown in Figure 2, and to provide one of the communicating openings 47 between each combustion chamber and one of the chambers 46 below the stills. In the arrangement shown therefore, there are four stills, each in line with one of the combustion chambers, and there is a passage 47 from each individual combustion chamber, to each individual chamber 46 below a still. The several stills are arranged progressively at different levels, starting with the still 48 on the right of Figure 1 at the highest level, and the still 49 next thereto at a slightly lower level; and the stills 50 and 51 are at progressively lower levels, so that oil or other liquid will flow by gravity through the several stills, starting in the right hand still 48

at Figure 1 and passing successively through the stills 49, 50, 51. To allow the progress of the liquid through the stills there is a pipe 52 connected with the interior of the still 48 with its open end extending upwardly and terminating at the point which will constitute the operating level of the oil in this first still. This pipe extends from the still 48 across to the second still 49, being provided with the valve 53 to control the flow of oil therein; and the other end of the pipe 52 extends upwardly within the second still and its upper open end is arranged at the height which is to constitute the operating level of the liquid in this tank; which level is preferably somewhat lower than the level in the first still in addition to the difference due to the different horizontal planes of the stills; that is to say, if the level of the first still is to be at the center of this still the level in the second still will preferably be slightly below the center line of this still. A similar pipe 54 having similar open ends, is connected between the still 49 and the third still 50 and the open ends of this pipe, lying within these respective stills, will likewise be arranged at the liquid level of the still 49 and the other at the liquid level of the third still 50 which latter level will preferably be lower than that of the second still. I depend to a great extent upon the difference in elevation of the several stills for the flow of the liquid progressively through them, but as vapors are evolved in each still naturally the quantity of liquid in the second still will be less than that of the first, due to the loss of these vapors, and likewise in the successive stills the quantity of liquid will be less than in each preceding still, and for this reason the several open ends of the connecting pipes are arranged at progressively lower levels than in the preceding stills in order to allow for the decrease in volume of oil as it progresses through the several stills. I have arranged at the rear of the row of stills suitable condensers 55, 56, 57, 58 one for each still, and the latter are connected by suitable pipes 59 with their respective condensers in order that the vapors evolved in each still may pass through the corresponding connecting pipe 59 into the corresponding condenser and in these condensers the vapors are condensed into liquid hydrocarbon products.

I have provided a condenser for reducing the vapors which pass from the retort, into liquid state before entering the stills as it is the intention to carry on the distillation process in the liquid phase. For this purpose the pipe 60 which receives the vapors from the collecting chamber 61 connects with a pump 62 which serves to create a partial vacuum in the collecting chamber and retort cylinder; and this pump delivers the vapors, together with any condensed liquid, through the coil of pipe 63 which is water-cooled, and

which forms a condenser for condensing the crude oil or whatever other product has been evolved in the retort chamber. From the coil of pipe 63 the condensed liquid, which 175 may be considered as crude oil for the purpose of illustration, is conducted through the pipe 64 into the first still 48. I have shown a valve 65, together with an outlet for conducting off any non-condensable gases, and 180 this may be carried to a suitable gas-holder from which the gas for operating the burners for heating retort and stills may be taken. It will be noted that the pipe 60 which 185 conducts the crude oil vapors to the vacuum pump is inclined, in order that the vapors will pass over in this pipe and any heavy oil which may have condensed up to this point will run back toward the left in Figure 1, 190 into the collecting chamber 61 and this heavier oil, together with any paraffin which may have collected in this chamber by condensation from the oil vapors passing through the vapor pipe 16 may be conducted from the chamber through a pipe 66 which is 195 controlled by a valve 67 into a residue receiver 68 arranged behind the third and fourth stills. I have also provided a pipe 69 controlled by a valve 70 for conducting the kerosene which has condensed in the second condenser 56 into the residue receiver 68. I 200 have also provided a connecting pipe 71 with a valve 77 with the third still 50 in which lubricating oil vapors are fractionated and this pipe delivers the residue from the third still into the residue receiver. The contents of the residue receiver are withdrawn by a 205 pressure pump 78 which forces it into the fourth still 51. This is a high pressure tank maintained at sufficiently high temperature, say 800 degrees, so that the liquid treated in this tank under a high pressure of several atmospheres is subjected to a cracking action for the purpose of increasing the gasoline production from the kerosene, lubricating oil 210 still residue and paraffin condensate. The volatiles produced in this high pressure tank are conducted by a pipe 59 into the condenser 58 associated with this still, wherein cracked volatiles are condensed.

50

Operation

The crushed shale or other carbonaceous material which is to be treated is continuously fed into the hopper 7 and it falls through the vertical tube 8 and past the air-seal valve 11 into the horizontal feed chamber 9 where it is taken by the screw conveyor 10 and forced along this chamber until it is delivered into the receiving end of the inclined revolving retort cylinder. In this cylinder the shale is caused to progress by gravity from the right to left hand end in Figure 1, the shale being continually turned over and agitated by the lifters 80. During the first part of the travel of the shale in the retort, it is sub-

jected to the heating action of the burners in the first fire box 30 which is sufficient to raise the temperature of the shale preparatory to the vaporizing of the hydro-carbons therein, but preferably the temperature is 70 not sufficient to actually release the oil vapors at this point. As the shale progresses to the next heat zone, in the retort, it will be subjected to the heat of the burners in the fire box 32 and in this heat zone the shale will 75 be raised to a higher temperature than when it was travelling in the first portion of the cylinder, or in the first heat zone. As the shale progresses, it is subjected to still greater heat by the burners in the fire box 34 and again by the heat of the burners in the fire box 35 which latter will raise the temperature of the shale to say 1100 degrees Fahrenheit, which will cause the immediate and complete release of oil vapors; and these vapors will 80 be drawn off by the partial vacuum into the collecting chamber 17, the rotary screen 18 serving to capture and throw down any particles of dust or solid matter which may be carried by the vapors and fixed gases. The 85 spent shale will fall out of the rear end of the retort cylinder into the tube 12 and from there it will pass into the horizontal chamber 13 where it is taken by the screw conveyor 14 and advanced to the discharge opening 15. The vapors which lie in the collecting chamber 17 pass into the pipe 16 and any paraffin condensing from the downward fractionating of these vapors collects in the chamber 61 and the remaining vapors are drawn 90 over through the pipe 60 and into the pump 62. From the pump the vapors are fed into the condenser 63 which reduces the vapors to the liquid state preparatory to its passage into the several stills. From this condenser 100 the crude oil passes through the pipe 64 into the first still, the fixed, combustive gas first escaping through the outlet 65 to a gas-holder. In this first still the oil is subjected to the heat generated by the burners in the fire 105 box 30 and which has primarily served to provide the heat for the first zone of the retort chamber, the residue of the products of combustion passing through the opening 47 in the wall 25, into the heating chamber 46, 110 under the first still where the products of combustion are again utilized for raising the temperatures of this still to the point where the gasoline content of the oil will be vaporized and pass through the corresponding pipe 115 59 into the condenser connected with this still. This condenser 55, therefore, will contain the first fraction which in the instance illustrated will be gasoline. The liquid from this first still 48 will flow by gravity through the pipe 52 into the second still. This latter still is heated by the waste products of combustion passing from the second fire box 32 through one of the openings 47 which travel 120 into the heating chamber 46 under this second 125 fire box 32.

still; and serve to heat the latter. As the waste products of combustion from this second burner compartment will be at a higher temperature than the products from the first 6 burner compartment, the still 49 will be raised to a higher temperature than the first still 48. Therefore the liquid in the still 49 will be heated to a sufficient degree to vaporize say the kerosene content of the oil, and 10 this will pass over through one of the pipes 59 into the second condenser 56 where it will be condensed into liquid hydro-carbon such as kerosene. The residue will flow also by gravity from the second still 49 through the 15 pipe 54 into the third still 50 ready for further treatment. This still is heated by the waste products of combustion in the fire box 32a passing through the opening 47 and into the chamber 46 under the third still. 20 These products of combustion will be sufficient to raise the temperature of the third still to a higher degree than that of the second still, so that the vapors formed in this third still will pass over in the pipe 59 to 25 the condenser 57 and the vapors condensed here will, in the illustration, constitute lubricating oil. The contents of the kerosene condenser are allowed to flow through the pipe 69 into the receiver 68 and the residue 30 of the third still 50 is also allowed to flow through the pipe 71 into the residue receiver; and any paraffin oil precipitated in the chamber 61 or any runback flowing in the pipe 60 will be conducted through the pipe 66 also 35 into the residue receiver. From this residue receiver the mixed oil is forced by the pressure pump 78 into the cracking still 51 where it is heated by the products of combustion passing from the fire box 35 to the chamber 40 46 under this still. The still will be raised in temperature preferably to about 800 degrees Fahrenheit, which, together with the pressure created therein, will cause the oil to be cracked and the vapors will pass over 45 through the pipe 59 into the condenser 58 which will condense cracked gasoline. In some cases it may be necessary to provide burners in the heating compartment 46 under the tank 51 to attain the cracking temperatures if the products of combustion from the fire box 35 are not sufficient to maintain the correct temperature. I have provided a 50 flue 81 communicating with all of the heat chambers 46 under the stills as a means for discharging the products of combustion into the smoke stack 82.

The shale is conducted through the retort by gravity, and the rotation of the retort tube and the oil evolved from the shale 60 is conducted partly or wholly by gravity successively through the several stills which are arranged at different levels in order to accomplish this gravity flow. By the arrangement of fire boxes and heating chambers 65 herein described, it is possible to maintain

progressively higher heating zones for the shale while it is progressing through the retort and it is also possible to make economical use of the products of combustion from the several fire boxes for the purpose of heating the several stills, and in such manner that the several stills are heated to the degrees necessary to accomplish fractional distillation throughout the series. By employing a high pressure and high temperature in the last still, I am enabled to crack the various residues in order to obtain a maximum gasoline yield from the oil. In other words, I have provided for a continuous retort action followed by continuous fractional distillation and cracking, the distillation and cracking being accomplished in the liquid phase and the entire operation being carried out with the greatest conservation of fuel.

Having described my invention, what I 85 claim is:

1. An apparatus of the class described, comprising a revolable cylinder through which carbonaceous material is adapted to travel, means enclosing said cylinder to form 90 separate heating chambers for heating the said cylinder in a plurality of heat zones lengthwise thereof, separate heating means in said chambers for heating different portions of said cylinder to relatively different temperatures, a plurality of stills and means connecting them in series whereby liquid will 95 travel successively through said stills, means for reducing the product evolved in said cylinder to the liquid phase and for delivering the same to the first of said series of 100 stills and means forming separate heating chambers under said separate stills and arranged to receive the products of combustion from said heating means in said first mentioned chambers. 105

2. An apparatus of the class described comprising a revolable cylinder through which carbonaceous material is adapted to travel, means enclosing said cylinder to form 110 separate heating chambers for heating the said cylinder in a plurality of heat zones lengthwise thereof, separate heating means in said chambers for heating different portions of said cylinder to different degrees of temperature, a plurality of stills and means connecting them in series, said stills being arranged in different horizontal planes whereby liquid will flow successively by 115 gravity through said stills, means for reducing the products evolved in said cylinder to the liquid phase and delivering the same into the first of said series of stills, and means forming separate heating chambers under 120 said stills, said latter heating chambers receiving the products of combustion from the heating means in said first chambers. 125

3. An apparatus of the class described comprising an inclined revolable retort cylinder through which carbonaceous ma- 130

terial is adapted to travel, means enclosing said cylinder to form separate heating chambers for heating the said cylinder in a plurality of heat zones lengthwise thereof, separate heating means in said chambers adapted to heat different portions of said cylinder to different degrees of temperature, a plurality of stills and means connecting them in series, said stills being arranged in different horizontal planes whereby liquid will travel successively through said stills by gravity, means for reducing the products evolved in said cylinder to the liquid phase and delivering the same into the first of said series of stills, and means forming separate heating chambers under the separate stills, said latter chambers receiving the products of combustion from the heating means in said first mentioned chambers.

4. An apparatus of the class described comprising an inclined, revolvable, retort cylinder through which carbonaceous material is adapted to travel, means enclosing said cylinder to form separate heating chambers for heating the said cylinder in a plurality of heat zones lengthwise thereof, separate heating means in said chambers adapted to heat different portions of said cylinder to different degrees of temperature, a plurality of stills and means connecting them in series said stills being arranged in different horizontal planes whereby liquid will travel successively through said stills by gravity, means for reducing the products evolved in said cylinder to the liquid phase and delivering the same to the first of said series of stills, means forming separate heating chambers under the separate stills, said latter chambers receiving the products of combustion from the heating means in said first mentioned chambers, and separate condensers for condensing the volatiles formed in the several stills.

5. An apparatus of the class described comprising an inclined revolvable retort cylinder through which carbonaceous material is adapted to travel, means enclosing said cylinder to form separate heating chambers for heating the cylinder in a plurality of zones lengthwise thereof, separate heating means in said chambers for progressively heating different portions of said cylinder to relatively higher degrees, a plurality of stills, means connecting said stills in series whereby liquid will travel successively through them and means forming separate heating chambers under the individual stills, said latter chambers receiving the products of combustion from said first mentioned heating chambers, and means for reducing the vapors evolved in said retort to the liquid stage and for delivering the liquid to the first of said series of stills.

6. An apparatus of the class described comprising an inclined revolvable cylinder through which carbonaceous material is

adapted to travel, means forming an enclosure around said cylinder and including lateral dividing walls for separating the space between said cylinder and enclosure into separate heating chambers, separate means in said chambers for heating different portions of said cylinder to relatively different degrees, stills, means connecting said stills in series whereby liquid will travel there-through successively and means forming heating chambers under the individual stills, said latter heating chambers receiving the products of combustion separately from said first heating chambers; and means for reducing the products evolved in said cylinder to the liquid phase and delivering the same to the first of said series of stills.

7. An apparatus of the class described comprising a revolvable retort cylinder through which carbonaceous material is adapted to travel, means enclosing said cylinder to form separate heating chambers for heating said cylinder in a plurality of heat zones lengthwise thereof, separate heating means in said chambers, a plurality of stills, means for connecting said stills in series whereby liquid will travel through them successively and means for reducing the products evolved in said cylinder to the liquid phase and delivering the same to the first of said series of stills, means forming heating chambers under the separate stills and separately receiving the products of combustion from said first heating chambers, and means for maintaining at least one of said stills under high pressure for cracking the product fed thereto.

8. An apparatus of the class described comprising a revolvable retort cylinder through which carbonaceous material is adapted to travel, means enclosing said cylinder to form separate heating chambers for heating said cylinder in a plurality of heat zones lengthwise thereof, separate heating means in said chambers, a plurality of stills, means connecting said stills in series whereby liquid will travel successively through them means forming heating chambers under the separate stills, said latter heating chambers receiving the products of combustion separately from the said first heating chambers means for reducing the products evolved in said cylinder to the liquid phase and delivering the same to the first of said series of stills, individual condensers for the respective stills for condensing the vapors evolved in the separate stills, the last still in the series comprising a high pressure cracking still, means for maintaining the same under pressure, and means for feeding the liquid from one of said condensers together with the residue from the still next preceding the cracking still to said cracking still for the purpose set forth.

9. An apparatus of the class described

comprising an inclined, revolvable, retort cylinder through which carbonaceous material is adapted to travel, means enclosing said cylinder to form separate heating chambers for heating the said cylinder in a plurality of heat zones lengthwise thereof, separate heating means in said chambers adapted to heat different portions of said cylinder to different degrees of temperature, a plurality of stills means connecting said stills in series whereby liquid will travel successively therethrough and means for reducing the product evolved in said cylinder to the liquid phase and delivering the same to the first of said series of stills and means forming separate heating chambers under the separate stills, said latter chambers separately receiving the products of combustion from said first chambers whereby said stills are heated relatively different degrees.

10. An apparatus of the class described comprising a revolvable retort cylinder through which carbonaceous material is adapted to travel, means enclosing said cylinder to form separate heating chambers for heating said cylinder in a plurality of heat zones lengthwise thereof, separate heating means in said chambers, a plurality of stills and means connecting said stills in series whereby liquid will pass successively therethrough, and means for reducing the product evolved in said cylinder to the liquid phase and delivering the same to the first of said series of stills, means forming heating chambers under the separate stills and separately receiving the products of combustion from said first heating chambers, means for maintaining at least one of said stills under high pressure for cracking the product fed thereto, individual condensers for condensing the vapors from the separate stills, and means for feeding the liquid from one of said condensers together with the paraffin condensate fractionated from vapors passing from the retort, to said cracking still.

11. An apparatus of the class described, including a revolvable retort cylinder through which carbonaceous material is adapted to travel, means enclosing said cylinder to form separate heating chambers for heating said cylinder in a plurality of heat zones lengthwise thereof, separate heating means in said chambers for heating different portions of said cylinder to relatively different temperatures, a plurality of stills and means connecting them in series whereby liquid will travel successively through said stills, a condenser and means for delivering the vapors evolved in said cylinder into said condenser in which latter the vapors are reduced to the liquid phase, means for delivering the condensed liquid from said condenser into the first of said series of stills, and means forming separate heating chambers under said separate stills and arranged

to receive the products of combustion from said heating means in said first mentioned chambers.

12. An apparatus of the class described, comprising a revolvable retort cylinder through which carbonaceous material is adapted to travel, means enclosing said cylinder to form separate heating chambers for heating said cylinder in a plurality of heat zones lengthwise thereof, separate heating means in said chambers for heating different portions of said cylinder to relatively different temperatures, a plurality of stills and means connecting them in series whereby liquid will travel successively through said stills, means for reducing the product evolved in said cylinder to the liquid phase and delivering the same into the first of said series of stills, means forming separate heating chambers under said stills and arranged to receive the products of combustion from said heating means in said first mentioned chambers, and separate condensers and means connecting them separately with said several stills whereby the vapors evolved in the several stills will be separately condensed.

Signed this 11th day of May, 1926 at Hudson, county of Columbia, and State of New York.
